Primary Examiner — Garth Rademaker*Assistant Examiner* — Samantha Q. Lawrence*(74) Attorney, Agent, or Firm* — Maschoff Brennan(57) **CLAIM**

The ornamental design for a cheek retractor device, as shown and described.

DESCRIPTION

FIG. 1 is a front perspective view of a cheek retractor device; FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown in FIGS. 1-8 illustrate portions of the cheek retractor device that form no part of the claimed design.
